CLAIM

The ornamental design for a lining for ash tray, dust bin, and the like, substantially as shown.

DESCRIPTION

FIG. 1 is perspective view from a side of a lining for ashtray, dust bin and the like, showing my new design; FIG. 2 is a perspective view from the top thereof; FIG. 3 is a top plan view thereof; and FIG. 4 is a side elevation thereof, each of the three sides being the same.

FIG.1
